UNITED STATES PATENT OFFICE

136,277

DESIGN FOR AN AIRPLANE

Donald B. Dailey, Santa Clara County, Calif., and
Robert Farrington, Auburn, N. Y.

Application November 28, 1942, Serial No. 108,904

Term of patent 3½ years

To all whom it may concern:

Be it known that we, Donald B. Dailey and Robert Farrington, citizens of the United States, and residing, respectively, near San Jose, in the county of Santa Clara and State of California, and at Auburn, in the county of Cayuga and State of New York, have invented a new, original, and ornamental Design for an Airplane, of which the following is a specification, reference being had to the accompanying drawings, forming a part thereof.

In the drawings:

Figure 1 is a side elevational view of an airplane showing our new design;

Figure 2 is a top plan view; and
Figure 3 is a front elevational view.

Figure 4 is a sectional view, taken on line 4—4 of Figure 2 and in the direction of the arrows.

Figure 5 is a sectional view taken on line 5—5 of Figure 2 and in the direction of the arrows; and

Figure 6 is a top perspective view thereof, shown to a somewhat reduced scale.

We claim:

The ornamental design for an airplane, as shown.

DONALD B. DAILEY.
ROBERT FARRINGTON.
